SLACK OR CUTTINGS REMOVING ATTACHMENT FOR KERF-CUTTING MACHINES

George Bodin, Chicago, Ill., assignor to Goodman Manufacturing Company, Chicago, Ill., a corporation of Illinois

Application February 22, 1943, Serial No. 476,728

2 Claims. (Cl. 262—30)

This invention relates to improvements in slack or cuttings removing attachments for kerf-cutting machines of the room and pillar type and has as its principal object to provide an efficient, compact, and relatively light cuttings removing device of the character described, so arranged as to readily remove the cuttings from the path of the cutter chain and capable of easy attachment or detachment from the kerf-cutting machine.

More particularly, my present invention relates to slack removing devices of the type broadly disclosed in Patent No. 2,278,796, which issued to T. E. Pray on April 7, 1942, wherein a continuous conveyer of the flight type is arranged to be driven from the power coupling of a mining machine, usually provided for driving a transporting truck from the rear end of the mining machine.

Other objects of my invention will appear from time to time as the following specification proceeds and with reference to the accompanying drawings wherein:

Figure 1 is a plan view of a kerf-cutting machine with a slack removing device constructed in accordance with my invention attached thereto, and with certain parts broken away and certain other parts shown in horizontal section;

Figure 2 is an enlarged rear end view of the kerf-cutting machine with the slack removing device attached thereto;

Figure 3 is a fragmentary view in substantially longitudinal section showing certain details of the slack removing device and the drive from the cutting machine gearing thereto;

Figure 4 is an enlarged detail fragmentary transverse sectional view taken through the cuttings removing conveyer;

Figure 5 is an enlarged detail fragmentary plan view with certain parts broken away and certain other parts shown in substantially horizontal section in order to illustrate certain details of the drive to the cuttings removing device;

Figure 6 is an enlarged detail fragmentary transverse sectional view taken through the drive to the cuttings removing device; and

Figure 7 is an enlarged fragmentary horizontal sectional view taken through the drive to the cuttings removing device and showing certain details thereof not shown in Figures 4 and 5.

Referring now in particular to the details of the embodiment of my invention illustrated in the drawings, a slack removing device generally indicated by reference character 10 is shown as applied to a kerf-cutting machine of the conventional room and pillar type indicated generally by reference char-

acter 11. Said kerf-cutting machine comprises a main frame 12 having a chain carrying cutter bar 13 projecting forwardly therefrom. Said cutter bar is supported in an underframe or cuttings channel disposed below said main frame between side walls 14, 14 and a base plate 15, said cuttings channel opening as usual to the rear of the machine. A cutter chain 16 is guided for movement about said cutter bar in a usual manner, and is driven from a cutter chain sprocket 17 on the lower end of a vertical shaft 18, selectively driven from a motor 19, disposed at the front of the main frame 12, in a manner which will hereinafter be more clearly described. A usual form of flexible feeding means is also provided to move the mining machine along the mine bottom on its bottom during the cutting and positioning operations. Said flexible feeding means, as herein shown, consists of a pair of winding drums 20, 20 disposed at opposite sides of the machine and suitably driven from the motor 19 in a usual manner. Said winding drums have flexible cables 21, 21 wound thereon adapted to be anchored at suitable points at opposite ends of the working place, to feed the cutter bar 13 into and across the coal face.

Kerf-cutting machines of the character herein described are usually transported from place to place on a wheeled truck (not shown) and while mounted on said truck the latter is driven from the motor 19 of the kerf-cutting machine. For this purpose the running gear of the truck is connected to a power take-off device 23 at the rear end of the mining machine, when the latter is mounted in transporting position on said truck. The means for driving said power take-off will more fully appear as the following specification proceeds. It will be understood, however, that when the machine is to be used for cutting coal, it is entirely withdrawn from the truck and is moved over the mine floor on its own bottom by means of the cables 21, 21. The slack removing device accordingly is preferably designed for attachment to the rear end of the kerf-cutting machine only during the actual cutting operation and is detached from the kerf-cutting machine when the machine is loaded on its truck for transportation.

Referring now in particular to the details of the slack removing device 10, which forms the subject matter of the present invention, said slack removing device includes an elongated frame 24 detachably secured to the rear end of the machine and extending transversely there- 55 of beyond the retreating side of the machine.

Said elongated frame is open towards the ground to permit the material removed from the path of the cutter chain by the conveying means to drop to the ground, and forms a support and guiding means for a pair of spaced endless chains 25, 25 having flights 26, 26 connected therebetween. Said flights depend from said chain during the conveying operation. As herein shown, said endless chains are trained about idlers 29, 29 on a shaft 30 extending longitudinally of the machine and mounted at the advance end of said frame in opposite sides thereof. From said idlers, said endless chains extend beneath the horizontal legs of angles 31, 31, forming a portion of said frame and also forming hold-down guides for said chain, to guide said chain in a horizontal path across the discharge end of the cuttings passageway formed by the side walls 14, 14 and the base plate 15 of the kerf-cutting machine, so the lower ends of the depending flights 26, 26 are disposed just above the mine bottom, to sweep the cuttings discharged by the cutter chain across the mine bottom. At the right-hand or retreating side of the machine said angles extend in an upwardly inclined direction and laterally beyond the retreating side of the machine, to and around idlers 33, 33 on a shaft 34, mounted at its ends in opposite sides of the machine and disposed a substantial distance above the ground, so the flights 26, 26 will pile the material discharged by the cutter chain 16 to the retreating side of the machine and will turn around said idlers at a point sufficiently above said pile, to prevent the carrying of the cuttings towards the machine by said flights. From said idlers, said chains extend in a downwardly inclined path along supporting guides 35, 35 of said frame. At the lower portion of their downward path of travel the supporting guides 35, 35 extend in an upwardly inclined direction to drive sprockets 36, 36 on a shaft 37, coaxial with and driven from the power take-off 23 in a manner which will hereinafter be described. At the point where said chains turn in an upwardly inclined path, the sides thereof opposite from the supporting guides 35, 35 are engaged by hold-down guides 38, 38, which guide said chains as they turn from a downwardly to an upwardly inclined path to the drive sprocket 36 (see Figure 2). From said drive sprockets, said chains extend in a downwardly inclined direction to and around the idlers 29, 29 and along the lower part of the cuttings discharge passageway. A cover 39 is provided to cover the upper part of said chain and frame and the flights 26, 26, to prevent injury to the machine operator.

The elongated frame 24 is detachably connected to the kerf-cutting machine by means of connecting brackets 41, 41 extending laterally and rearwardly from opposite sides of the side walls 14, 14, in parallel relation with respect thereto and terminating a slight distance behind the rear end of said side walls. Said connecting brackets are adapted to be engaged between the bifurcations of bifurcated connecting lugs 43, 43 extending from the inner side of the frame 24 towards the kerf-cutting machine. Pins 44, 44, adapted to register for engagement with apertured portions of said connecting brackets and lugs, are provided to detachably hold the lower portion of said frame to the lower portion of the kerf-cutting machine.

The upper portion of the frame 24 is detachably connected to the kerf-cutting machine by

means of a frame and housing 45, which forms a bearing support for the longitudinally extending shaft 37, on which the spaced drive sprockets 36, 36 are keyed. Said housing, as herein shown, is of a split construction including an outer half 47 having a rearwardly projecting bracket 48 secured to and forming a part of the frame 24, which bracket has the drive shaft 37 journaled therein. Said housing also includes an inner half 49 having an inwardly extending annular portion 50, which fits within a recess 51 formed in the rear wall of the main frame 12 of the kerf-cutting machine. Said recess is of a cylindrical formation and is disposed concentric with the power take-off 23. Said inner half of said housing is provided with a boss 53 which, as herein shown, extends within a socket 54 of the power take-off and has a longitudinally extending shaft 55 journaled thereon. A drive member 56 is formed on the inner end of the shaft. Said drive member is of an irregular formation and is adapted to engage the socket 54, which likewise is of an irregular formation, so said socket will rotatably drive said drive member and shaft. A spur gear 57 is keyed on said shaft and meshes with and drives a spur gear 58 on the shaft 37, for driving the endless chains 25, 25 from the kerf-cutting machine. A plurality of cap screws 52, 52 extending through said housing and threaded in the rear end of the frame 12, are provided to detachably secure said housing and the frame 24 to the upper part of said cutting machine frame.

The drive from the motor 19 to the power take-off 23 and socket 54 includes a longitudinal shaft 59 journaled in the frame 12 and driven from the rear end of the motor 19 through a suitable spur gear reduction (not shown). A coaxial shaft 60 is driven from the rear end of said shaft 59 by means of a coupling 61. Said shafts are coaxial with the power take-off 23 and said power take-off is keyed to and driven from the rear end of said shaft 60.

A cuttings sweep indicated at 62 is provided to aid the cutter chain in propelling the cuttings beyond the rear end of the machine into the path of the flights 26, 26. Said sweep, as herein shown, is secured to the lower end of the vertical shaft 18, just beneath the sprocket 17, as by a nut 63, and has four radially extending arms 64, 64 extending horizontally in close relation to the base plate 15 well beyond the outer reach of the cutter chain, close to the discharge opening of the cuttings path. Said radially extending arms are each provided with a vertical propelling web 65 extending longitudinally therewith and conforming substantially to the angle of inclination of the extreme down block of the cutter chain 16 at their inner ends.

The drive from the motor 19 to the sweep 62 and the cutter chain drive sprocket 17 includes a bevel pinion 66 keyed on the longitudinal shaft 59 and meshing with a bevel gear 67 secured to the upper end of a flanged portion of a drive sleeve 68. Said drive sleeve is journaled on the vertical shaft 18 on ball bearings 69, 69 and has an internally splined clutch member 70 splined thereon. The splines of said clutch member are adapted to engage a splined member 71, keyed on the vertical shaft 18, for driving said shaft. A suitable system of links and levers is provided to shift said clutch member, which is not herein shown or described since it is no part of my present invention.

While I have herein shown and described one

form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a kerf-cutting machine having a frame, a cutter bar having a portion extending through a cuttings passage opening to the rear end of said frame, a cutter chain guided for orbital movement about said cutter bar, a cutter chain drive sprocket for driving said cutter chain about said cutter bar, a rotatable cuttings sweep disposed beneath said sprocket, coaxial with the axis of rotation thereof, to assist the cutter chain in discharging the cuttings through said cuttings passage beyond the rear end of the machine, and a cuttings discharge conveyer extending across and detachably mounted on the rear end of said frame and driven from the kerf-cutting machine, said conveyer including a frame extending across said cuttings passage laterally beyond the retreating side of the machine, a chain conveyer guided for movement about said frame and having flights depending from said frame, when traveling across said cuttings passage, said frame being open towards the ground throughout its length and having a horizontal portion extending across the discharge opening of said cuttings passage, adjacent but spaced above the ground a distance sufficient to permit said flights to convey the cuttings discharged by said sweep along the ground beyond the retreating side of the machine, and having an upwardly inclined portion extending laterally beyond the retreating side of the machine for elevating said chain and flights above the ground.

to clear said flights from the discharged cuttings as they reverse their direction of travel along said frame.

2. In a kerf-cutting machine having a frame having a cuttings passageway extending therethrough and opening at the rear end thereof, a cutter chain carrying cutter bar extending through said cuttings discharge passageway and projecting beyond the front end of said frame, a cuttings discharge conveyer extending across the discharge end of said cuttings passageway and including a frame extending across the rear end of said frame and beyond the retreating side thereof, a pair of endless chains guided for movement along said frame and having spaced flights depending therefrom to a point close to the ground when traveling across said frame, for conveying the cuttings along the ground transversely of said frame beyond the retreating side of the machine, the portion of said conveyer extending beyond the retreating side of the machine being upwardly inclined and said conveyer reversing its direction of travel at a point spaced above the ground a distance sufficient to prevent the scattering of the cuttings by said flights, as said flights turn about said frame on their return path, a geared reduction drive detachably connectible with the gearing of said kerf-cutting machine, for driving said conveyer and including a housing encasing said drive and secured to said conveyer frame and having bearing means for said drive, and means for detachably connecting said conveyer to said kerf-cutting machine including means for connecting said conveyer to opposite sides of said frame adjacent the lower end thereof, and means for securing said housing to said kerf-cutting machine frame at a point spaced above and intermediate the points of connection of said conveyer to said frame.

GEORGE BODIN.
